ATTORNEY

UNITED STATES PATENT OFFICE.

SETH A. CRONE, OF NEW YORK, N. Y.

BRAKE-BEAM.

SPECIFICATION forming part of Letters Patent No. 752,045, dated February 16, 1904.

Application filed September 23, 1903. Serial No. 174,257. (No model.)

To all whom it may concern:

Be it known that I, SETH A. CRONE, a citizen of the United States, and a resident of New York, in the county of New York and State of New York, have invented certain new and useful Improvements in Brake-Beams, of which the following is a specification.

The invention relates to improvements in brake-beams for railway-cars; and it consists in the novel features of construction and combinations of parts hereinafter described, and particularly pointed out in the claims.

Brake-beams of the class to which my invention pertains comprise a rolled body beam or member of suitable length, brake-heads of standard construction on the ends thereof, a fulcrum for the brake-lever, wheel-guards secured to said body-beam adjacent to said brake-heads, and means for attaching the pendent safety-chains; and my invention has for its object to produce novel wheel-guards to be applied to the body-beam and novel means for attaching the lower ends of the safety-chains to said beam.

The purposes of my invention are to produce a more durable and less expensive structure than those heretofore known, and preferably to form the wheel-guards and clips for the safety-chains in one integral piece of forged metal.

The invention will be fully understood from the detailed description hereinafter presented, reference being had to the accompanying drawings, in which—

Figure 1 is a top elevation of a brake-beam employing wheel-guards and chain-clips constructed in accordance with and embodying the invention, the fulcrum and brake-heads being omitted. Fig. 2 is an enlarged end view of same, the rolled body-beam being indicated by dotted lines. Fig. 3 is an enlarged top view of one of the wheel-guards and chain-clips embodying my invention. Fig. 4 is an enlarged perspective view of same, a portion of the chain-clip being shown in the position which will be imparted to it preparatory to the application of the safety-chain thereto; and Fig. 5 is an outer end view of one of the wheel-guards.

In the drawings, 10 designates a usual body-

beam of rolled metal, 11 the wheel-guards of my invention, and 12 the chain-clips, the latter and the wheel-guards being preferably in one integral piece of forged metal and said beam 10 having usual flanges 13. The wheel-guards 11 and clips 12 are preferably integral with each other and formed of one piece of metal pressed to shape and constituting in the complete article the concavo-convex arm 14 and the flanges 15, 16, 17, and 18, the flange 17 bearing against the web of the beam and secured thereto by the rivet or bolt 19, extending through an aperture 20 in said flange 17 and through an aperture formed in said web, as represented in Figs. 1 and 2. The flanges 16, 15 engage the opposite sides of the flange 13 of the beam 10, a recess 21 being formed between said flanges 16, 15 to receive at the upper side of the beam 10 the said flange 13. The flanges 16 and 15 coöperate with the flange 13 of the body-beam in affording adequate support for the projecting arm 14, which extends outwardly from the flange 15 substantially in line with the web of said body-beam. The arms 14 are made of concavo-convex form in cross-section, and the convex face of said arm 14 faces upwardly, whereby the said arm 14 is rendered stiff and durable without the employment of an excessive weight of metal, and the upper surface of said arm 14 will shed any water or dust which may settle thereupon.

The flange 17 constitutes the means, in connection with the rivet 19, for securing the arm 14 to the beam 10 and also the means for securing the flange 18 to said beam, said flange 18 being projected upwardly from the web of the beam 10 and constituting the clip for receiving the lower end of the safety-chain. The flange 18 will be provided with an aperture 21, extending transversely through it and substantially in line with the width of the beam 10 to facilitate the application of the lower end of the chain (not shown) to said flange 18. I shall preferably split the flange 18 at one side of its aperture 21, as more clearly illustrated in Fig. 4, thereby providing a section 22 of said flange which may be bent outwardly from its normal position (shown by dotted lines in Fig. 4) to the position in which

it is illustrated by full lines in Fig. 1 for the purpose of opening the aperture 21 and permitting the lower link of the usual safety-chain to be slipped upon the said section 22 and passed to the said aperture 21, after which the said section 22 will be bent back to its normal position for the purpose of closing the said aperture 21 and locking the chain in position. It will not always be necessary to split the flange 18 or form the section 22; but considerable labor will be saved when the said flange is thus split, because of the convenience afforded thereby for securing the safety-chain to the beam.

15 I do not limit my invention in every instance to the manufacture of the flange 18 in one integral piece with the wheel-guard arm 14, because for some classes of brake-beams the wheel-guard arms 14 are not employed. 20 Neither do I limit the invention in every instance to the manufacture of the wheel-guard arm 14 in one integral piece with the flange 18, because the wheel-guard arm 14 is novel in itself when the flange 18 is omitted. It is possible also to employ the wheel-guard arm 14 and a chain-clip of a construction other than that shown in the drawings, and although I prefer to make the chain-clip and the wheel-guard arm in one integral piece of metal it is evident that the chain-clip may be constructed of an independent piece of metal and bolted to the beam 10. In instances in which I shall not employ the chain-clip in one piece with the wheel-guard arm 14 the wheel-guard will then comprise the flanges 17, 16, 15 and arm 14, and in instances in which the wheel-guard is entirely omitted, but the chain-clip employed, the chain-clip will comprise the flanges 17 and 18. I prefer to employ the flange 15, so as 40 to throw the wheel-guard arm 14 about in line with the web of the beam 10; but in some instances the arm 14 may extend directly outward from the edge of the flange 13 of the beam 10, the flange 15 then not being employed.

45 It will be observed that the aperture 21 in the flange 18 is located at one side of the center of said flange, this being the preferred arrangement of said aperture.

50 The piece of metal from which the combined wheel-guard and chain-clip hereinbefore described is formed is, as will be observed, a flat bar of forged metal of substantially uniform width and thickness and greater in width than in thickness and pressed to shape.

55 What I claim as my invention, and desire to secure by Letters Patent, is—

1. In a brake-beam, the body-beam and the wheel-guard secured thereto, said wheel-guard comprising in one integral piece of forged metal, the flanges 17, 16 and projecting arm 14, the latter being of concavo-convex form; substantially as set forth.

2. In a brake-beam, the flanged body-beam and the combined wheel-guard and chain-clip 65 secured thereto and being in one integral bar of forged metal greater in width than in thickness, said wheel-guard and chain-clip comprising the flanges 18, 17, 16 and 15 and projecting arm 14, said flanges 17, 16 and 15 closely 70 fitting the body-beam and said arm 14 extending outwardly from the lower end of said flange 15, and said flange 18 extending upwardly from the web of the body-beam with its flat faces in line with the length of the 75 wheel-guard and containing the aperture 21 extending transversely through it; substantially as shown and described.

3. In a brake-beam, the body-beam and the wheel-guard secured thereto, said wheel-guard 80 comprising in one integral piece of metal the flanges 17, 16 and 15 and projecting arm 14, the latter being of concavo-convex form; substantially as set forth.

4. In a brake-beam, a body-beam and the 85 combined wheel-guard and chain-clip secured thereto and being in one integral piece of metal, said wheel-guard and chain-clip comprising the flanges 18, 17 and 16 and projecting arm 14, the whole being of forged metal 90 and said arm 14 being concavo-convex in cross-section; substantially as set forth.

5. In a brake-beam, a body-beam and the combined wheel-guard and chain-clip secured thereto and being in one integral piece of 95 metal, said wheel-guard and chain-clip comprising the flanges 18, 17 and 16 and projecting arm 14, the said flange 18 having the aperture 21 and being split outwardly therefrom so as to form the section 22, and the 100 whole being of forged metal; substantially as set forth.

6. In a brake-beam, the body-beam and the combined wheel-guard and chain-clip secured thereto and being in one piece of forged metal, 105 said chain-clip comprising an apertured flange 18 split outwardly from the aperture therein; substantially as set forth.

7. In a brake-beam, the body-beam and the chain-clip secured thereto, said chain-clip comprising the flange 17 and apertured flange 18, the latter being split outwardly from the aperture therein; substantially as set forth.

8. In a brake-beam, the body-beam and the chain-clip secured thereto, said chain-clip comprising the flange 18 having the aperture 110 therein and being split outwardly from said aperture; substantially as set forth.

Signed at New York, in the county of New York and State of New York, this 21st day of September, A. D. 1903.

SETH A. CRONE.
